UNITED STATES PATENT OFFICE.

HARRY D. NEFF, OF CAMBRIDGE, MASSACHUSETTS, ASSIGNOR TO RE-FILIT BROOM COMPANY, OF BOSTON, MASSACHUSETTS, A CORPORATION OF MASSACHUSETTS.

BROOM OR BRUSH UNIT.

1,411,221.

Specification of Letters Patent. Patented Mar. 28, 1922.

Original application No. 373,595, filed April 13, 1920. Divided and this application filed December 11, 1920. Serial No. 430,099.

To all whom it may concern:

Be it known that I, HARRY D. NEFF, a citizen of the United States, and resident of Cambridge, in the county of Middlesex and 5 State of Massachusetts, have invented an Improvement in Broom or Brush Units, of which the following description, in connection with the accompanying drawings, is a specification, like letters on the drawings 10 representing like parts.

My present invention relates to brooms of the sectional type, and more particularly to an improved broom unit for use in such brooms.

15 In brooms of the sectionable type, considerable difficulty has been experienced in devising a broom unit that will be readily manufactured and assembled in the broom holder and remain in position therein.

20 When the units are assembled in the chamber of the holder, it has heretofore been impossible to prevent undue movement of the units relative to the holder, this movement being more apparent when the broom is being used.

25 In my copending application, Ser. No. 373,595, filed April 13, 1920, of which the present application is a division, I have shown and described an improved broom holder adapted to receive and hold a plurality of broom units such as form the subject 30 matter of the present invention. In making these broom units, I have devised a binding means that is simple in character, and which hold the fibres rigidly in position, the 35 form of binding means preventing swelling of the unit, due to moisture, at the place of binding.

The object of my invention, therefore, is an improved broom unit for sectional brooms 40 and the like.

In the accompanying drawing illustrating the preferred embodiment of my invention,

Fig. 1 is a side elevation;

Fig. 2 is a front elevation;

45 Fig. 3 is a sectional view on the line 3—3 of Fig. 2; and

Fig. 4 is a sectional view through a sectional broom.

Referring to the drawings, my improved

form of broom or brush unit is comprised 50 essentially of a bundle of fibres or bristles 10, parallelly arranged with respect to each other, and over this bundle 10 I place a sleeve or band 11 of metal or other suitable material. This band 11 is placed on the 55 bundle so as to have the butt or stalk ends of the fibres extend beyond the end of the sleeve or band. When placed on the bundle the sleeve or band is substantially cylindrical 60 in shape, and I compress the sleeve or band so that it is substantially oval in cross-section, as shown in Fig. 3, grooves or V-shaped indentations 12 being formed at opposite sides 65 of the sleeve or band and which securely hold the band in position. Even though the metal 70 or other material of which the sleeve or band is composed may be quite thin, the grooves 12 stiffen the structure to such an extent that the sleeve or band cannot be deformed through ordinary usage. Viewed from the 75 front, as in Fig. 2, the sides of the sleeve or band 10 are parallel, while viewed from the side, as in Fig. 1, the upper portion 13 of the sleeve or band is cone shaped, the lower portion 14 being parallel sided.

In use I assemble a plurality of bundles or units in a holder 15, such as is shown in Fig. 4, and which is claimed in my copending application above referred to, this holder having a chamber defined by front, back 80 and end walls, and a diaphragm 16. A cover or closure 19, having the same contour as the front wall, is used for maintaining the bundles in the chamber. The chambers, at a point intermediate its upper and lower 85 ends, is of the same shape as the band 10, viewed in side elevation, as in Fig. 1. When assembled in the chamber, the butt or stalk ends of the fibres spread out to fill the upper part of the chamber, while the closure or 90 cover 19, on being forced into position acts on the cone shaped portion of the sleeve or band to force the same upwardly and thus hold said bundles securely in position.

While I have shown and described the 95 preferred embodiment of my invention somewhat in detail, it is to be understood that I may vary the details of the construction and

arrangement of parts constituting my invention within wide limits without departing from the spirit of the invention.

My invention is further described and defined in the form of a claim as follows:

A brush or broom unit comprising a bundle of fibres, a thin metallic sleeve substantially circular in cross-section at one end

and tapering on each side and substantially oval shape at the other end, and a V-shaped indentation extending longitudinally of the sleeve and on each side thereof for compressing and binding the fibres in the sleeve.

In testimony whereof, I have signed my name to this specification.

HARRY D. NEFF.
